UNITED STATES PATENT OFFICE.

DANIEL A. HOPPING, OF STURGIS, MICHIGAN.

BOOK-MAKING MACHINE.

1,282,834.

Specification of Letters Patent. Patented Oct. 29, 1918.

Application filed October 15, 1917. Serial No. 196,646.

To all whom it may concern:

Be it known that I, DANIEL A. HOPPING, a citizen of the United States, residing at Sturgis, county of St. Joseph, State of Michigan, have invented certain new and useful Improvements in Book-Making Machines, of which the following is a specification.

This invention relates to improvements in book making machines.

10 My improvements are especially designed by me for applying covers to sales books and the like, although they are adapted and desirable for use in applying covers to tablets and other books or pads.

15 The main objects of this invention are:

First, to provide a machine for applying covers to sales books and the like which is automatic in its operation and of large capacity.

20 Second, to provide a machine having the above recited advantages which is comparatively simple and economical in structure and durable in use.

Third, to provide an improved machine 25 having these advantages requiring but little attention on the part of the operator.

Further objects, and objects relating to structural details, will definitely appear from the detailed description to follow.

30 I accomplish the objects of my invention by the devices and means described in the following specification. The invention is clearly defined and pointed out in the claims.

35 A structure which is a preferred embodiment of my invention is clearly illustrated in the accompanying drawing, forming a part of this specification, in which:

Figure I is a plan view of a structure embodying the features of my invention, the 40 stapler being shown conventionally and portions broken away.

Fig. II is a front side elevation.

Fig. III is a detail rear side elevation with 45 parts shown in vertical section.

Fig. IV is a detail elevation of the front end of the machine.

Fig. V is a detail vertical longitudinal section on a line corresponding to line 5—5 50 of Fig. I.

Fig. VI is an enlarged detail vertical longitudinal section on a line corresponding to line 6—6 of Fig. I, showing details of the cover feed mechanism.

Fig. VII is an enlarged detail vertical 55 transverse section on a line corresponding to line 7—7 of Figs. I and II, showing further details of the cover feed mechanism.

Fig. VIII is a detail vertical transverse section on a line corresponding to line 8—8 60 of Figs. I and II, showing details of the binding flap turning means.

Fig. IX is a detail vertical transverse section on a line corresponding to line 9—9 65 of Figs. I and II, showing details of the sheet delivery mechanism.

Fig. X is a detail plan view with parts broken away, showing further details of the sheet delivery and cover folding mechanism.

Fig. XI is a detail transverse section on a line corresponding to line 11—11 of Figs. I and II, showing further details of the cover 70 folding mechanism.

Fig. XII is an enlarged detail longitudinal section on a line corresponding to line 12—12 of Fig. I, showing details of the discharge mechanism.

Fig. XIII is an enlarged detail cross section through the conveyer on a line corresponding to line 13—13 of Fig. X.

Fig. XIV is a longitudinal section through one of the completed books.

In the drawing similar reference characters refer to similar parts throughout the 85 several views, and the sectional views are taken looking in the direction of the little arrows at the ends of the section lines.

Referring to the drawing, 1 represents the stapler which is supported by a suitable 90 pedestal 2. As the details of the stapler and driving means therefor form no part of this invention they are not illustrated or described herein.

The stapler pedestal is preferably utilized 95 as a support for one end of the frame, designated generally by the numeral 3. The other end of the frame is supported by legs or standards 4.

At the ends of the frame I mount the 100 sprocket wheels 5 and 6 for the conveyer chains 7. The upper reaches of the conveyer chains travel on ways 7'. These conveyer chains are provided with cross pieces 8 on which are mounted coacting pairs of 105 flights 9 and 10 forming pockets adapted to receive the covers and sheets, as will be hereafter described.

The forward flight 10 of each pair is provided with a rearward extension 11 which assists in discharging the stapled books from the conveyer, as will hereafter be described.

5 The driving shaft 12 is connected by the sprocket wheel 13 and chain 14 to the driving mechanism of the stapler, not here illustrated. On this shaft 12 is a crank disk 15 connected by the pitman 16 to the pawl 17 carrying rocker 18 which is pivoted on the shaft 18 and provided with a pawl 19 coacting with the ratchet wheel 20. The shaft 18 is provided with a sprocket wheel 21 connected by the sprocket chain 22 with the 15 sprocket wheel 23 on the shaft 24 of the conveyer sprocket wheels 5. This ratchet mechanism drives the conveyer with a step-by-step movement which is timed with the stapler. A tension idler 25 is provided for the chain 22.

20 The covers are placed in a hopper 26 disposed at the front end of the conveyer. The covers are fed to the conveyer by the reciprocating feed member 27. This feed member is connected by the link 28 to an arm 29 on the rock shaft 30. This rock shaft is provided with an arm 31 connected by the link 32 to the lever 33 pivoted at 34 and slotted at 35 to receive the crank pin 36 on the 30 crank 37. This crank 37 is on a shaft 38 provided with a sprocket wheel 39 connected by the sprocket chain 40 to a sprocket wheel 41 on the driving shaft 12.

35 The actuation of the cover feed slide is timed so that the covers are delivered into the conveyer pockets. However, the covers are not ejected from the hopper until the front flights 10 are substantially at the top of the front conveyer sprocket wheels.

40 Mounted on the shaft 42 of the front conveyer sprocket wheels 6 and at the outer sides thereof are friction feed rollers 43 adapted to engage the covers when ejected by the feed member and carry them along 45 until they are positively engaged by the rear flights or pocket members. Pressure feed rollers 44 carried by the fixed arms 45 are supported above the rollers 43 so that they hold the covers in effective frictional engagement therewith and insure their being 50 fed into the pockets.

45 The covers 46 are scored previous to placing in the hopper along the dotted lines 47 and 48 to facilitate folding. The dotted lines 47 are the binding flap folding scores, and the lines 48 the cover extension or closing flap scores. In practice, the covers are printed and scored at the same operation. As the covers are carried along by the conveyer their binding flaps 47' are carried below the fixed flap turning member 49 which is, in the structure illustrated, yoke-shaped in cross-section, its outer arm being mounted on the vertical guide 50,—see Fig. VIII.

55 While the covers are positioned under this

fixed flap turning member the binding flaps are engaged by the reciprocating flap turner 51. The flap turner 51 is supported in brackets 52 and actuated by a lever 53 pivoted at 54 on the arm 55 extending from the frame. This lever is actuated by a tappet 56 on the crank 37. A coiled spring 57 is connected with the opposite end of the lever to return the flap holder to its initial position when released by the tappet. This 75 provides a quick actuation for the reciprocating flap turner.

As the covers are carried along they pass under the pad hopper 58 with their upturned binding flaps against the guide and abutment 59. In this position one of the pads or bundles of sheets 60 is ejected by the feed slide 61 under the pressure member 62 with the binding edge of the pad against the binding flap, as clearly shown in Fig. IX. 85

90 The feed member 61 reciprocates in ways 63. As the covers are carried along by the conveyer their closing flap extensions 48' are supported by the flat way 64. A strip 65 is disposed at the side of the conveyer 95 so that the cover extensions slide along under the strip which prevents their being displaced from the conveyer pockets as they are carried along and operated upon by the binding flap turner. The cover extensions 48' pass below the feed member 61 and to effectively guide them below the same a guide 66 is disposed at the front side of the hopper. A guide 66 projects from the hopper under the pressure member 62 preventing the uptilting of the sheets as they are 100 discharged from the hopper between the flights and upon the covers.

105 The sheets are preferably stapled in pads, a suitable machine for the purpose being shown in my copending application for Letters Patent, Serial No. 196,415, filed Oct. 13, 1917. As the covers with pads therein are advanced from this position the cover extensions are engaged by the flap turner 67 110 and swung to a position in front of the cover extension folder 68, which is mounted on the reciprocating plunger rod 69 carried by the support 70 on the shelf-like frame extension 71. This plunger rod 69 is returned 115 to its initial position by the spring 72 arranged thereon, as shown in Fig. IX.

120 The plunger 69 is operated by the arm 73 on the rock shaft 74, the rock shaft being provided with a second arm 75 projecting 125 into the path of the tappet 76 on the link 77 constituting a part of the actuating connections for the feed slide 61. This link 77 is mounted on the lever 78 pivoted at 79 and connected by the link 80 to the cam actuated slide 81. The slide 81 is actuated by the cam 82 on the shaft 39,—see Fig. IX. The driving connections for this shaft have been described. The flap turner 67 is extended rearwardly and constitutes an abutment for 130

the front end of the books, it being yieldingly supported by the rods 67' and the spring 67" to press the books rearwardly against the rear guide 59.

- 5 The folder 68 folds the cover extensions 48' upon the pads, so that they are carried under a clamping means comprising cross bars 83 mounted on sprocket chains 84 supported by sprocket wheels 85 arranged so 10 that the lower reaches of the chains travel in a plane parallel to the upper reach of the conveyer and in a spaced relation thereto, so that the cross pieces engage the pads with the covers folded thereon and travel along 15 therewith, as shown in Fig. V.

The shaft 86 of one of the sprocket wheels is connected by the sprocket chain 87 and suitable sprocket wheels to a shaft 88 which is provided with a sprocket wheel 89 driven by one of the conveyer chains 7. The shafts 20 of the sprocket wheels 85 are connected by the sprocket chain 85' and suitable sprocket wheels.

As a pad is carried along, the upstanding binding flap is engaged and turned by the flap turner 90 and carried under it and held in folded position until the staples are inserted. The completed books are discharged as the flights pass over the rear conveyer 25 sprocket 5, the extensions 11 of the flights being adapted to tilt the books from the conveyer pockets so that they are deposited in the rack 91. To prevent the cover extensions 30 swinging open when the books are discharged I provide a curved arm 92 which projects rearwardly over the rear conveyer sprocket wheels. The finished books may be lifted from the rack in bundles ready for 35 packing.

40 I have described the various mechanisms and operations practically in the order of operation, but in the interests of clearness will point out the general cycle of operations. The stapling mechanism is automatic 45 in its operation and the conveyer is timed to the operation thereof. Ordinarily all that is required of the operator is to keep the cover and sheet hoppers filled and remove the stapled books.

50 Covers are discharged from the hopper one by one and delivered into the conveyer pockets by the reciprocating feed member and the feed rollers. As the covers are carried along by the conveyer the binding flap 55 is turned upwardly by the binding flap turners 49 and 51 after which they are carried below the pad hopper and the pads ejected thereon with their binding edges abutting the upstanding binding flaps. As they are 60 further carried along, the cover extensions are turned up by the extension turner 67 and engaged by the extension folder 68 which folds the extension flaps down upon the sheets. The binding flap is engaged by the 65 flap turner 90 and turned down upon the

sheets in position to receive the staples. The books with folded covers are then engaged by the movable guide means described and are clamped thereby during the stapling operation and while they are advanced to the 70 discharge.

By my improved mechanism I am able to manufacture books of the class described rapidly and uniformly and without distortion 75 of the sheets.

I have illustrated and described my improvements in an embodiment which I have found entirely practical. I have not attempted to illustrate or describe certain modifications in structural details which I 80 contemplate and which might be desirable for certain adaptations, as I believe the disclosure made will enable those skilled in this art to embody or adapt the same as may be desired.

Having thus described my invention, what I claim as new and desire to secure by Letters Patent, is:

1. The combination of a conveyer comprising sprockets and sprocket chains provided with pairs of flights coacting to provide pockets, means for driving said conveyer step by step, a cover hopper disposed at the front end of the conveyer, a reciprocating feed member disposed to deliver covers from 90 the hopper to the said conveyer tangentially of the front sprockets, friction feed rolls mounted axially with and at the outside of the front sprockets to engage the covers as they are delivered by said cover feed member and carry them into the pockets with their ends projecting at each side thereof, and means for holding the covers in frictional engagement with the feed rollers.

2. The combination of a conveyer comprising sprockets and sprocket chains provided with pairs of flights coacting to provide pockets, a reciprocating feed member disposed to deliver to the said conveyer, friction feed rolls mounted axially with and at 110 the outside of the front sprockets to engage the articles as they are delivered by said feed member and carry them into the pockets, and pressure rollers disposed above said feed rollers to coat therewith.

3. The combination of a conveyer comprising sprockets and sprocket chains provided with pairs of flights coacting to provide pockets, a reciprocating feed member disposed to deliver to the said conveyer, friction feed rolls mounted axially with and at 120 the outside of the front sprockets to engage the articles as they are delivered by said feed member and carry them into the pockets, and means for holding the covers in frictional engagement with the feed rollers.

4. The combination of a conveyer provided with pairs of flights coacting to provide pockets, a cover hopper disposed at the front end of the conveyer, a reciprocating 130

feed member disposed to deliver covers from the hopper to the said conveyer, friction feed rolls mounted to engage the covers as they are delivered by said cover feed member and 5 carry them into the pockets with their ends projecting at each side thereof, and pressure rollers disposed above said feed rollers to coat therewith.

5. The combination of a conveyer provided with pairs of flights coacting to provide pockets, a cover hopper disposed at the front end of the conveyer, a reciprocating feed member disposed to deliver covers from the hopper to the said conveyer, friction feed 10 rolls mounted to engage the covers as they are delivered by said cover feed member and carry them into the pockets with their ends projecting at each side thereof, and means for holding the covers in frictional engagement with the feed rollers.

6. The combination of a conveyer, means for delivering covers into said conveyer with their ends projecting at each side thereof, a fixed binding flap turner member supported 15 to overhang the binding flaps projecting at the rear of said conveyer, a reciprocating flap turner member disposed to fold flaps up against the fixed member, a guide disposed to support the upturned binding flaps, means for delivering pads to the conveyer with their binding edges against the upturned binding flaps, and means for folding the binding flap upon the binding edges of the pads.

35 7. The combination of a conveyer, means for delivering covers into said conveyer with their ends projecting at each side thereof, a fixed binding flap turner member supported to overhang the binding flaps projecting at 20 the rear of said conveyer, a reciprocating flap turner member disposed to fold the flaps up against the fixed member, a guide disposed to support the upturned binding flaps, and means for folding the binding 30 flap upon the binding edges of the pads arranged thereon.

8. The combination of a conveyer, means for delivering covers into said conveyer with their ends projecting at each side thereof, means for turning the binding flaps of the covers to an upright position, a pad hopper disposed so that the projecting front edges of the pads pass under the same, a pad feeding member delivering the pads to the conveyer upon the covers with the binding edges of the pads against the upturned binding flaps thereof, and means for folding the binding flap upon the binding edges of the pads.

60 9. The combination of a conveyer, means for delivering covers into said conveyer with their ends projecting at each side thereof, means for turning the binding flaps of the covers to an upright position, means for delivering pads to the conveyer with their

binding edges against the upturned binding flaps, and means for folding the binding flap upon the binding edges of the pads.

10. The combination of a conveyer, means for delivering covers into said conveyer with 70 their ends projecting at each side thereof, means for turning the binding flaps of the covers to an upright position to receive pads, and means for folding the binding flap upon the binding edges of the pads arranged 75 thereon.

11. The combination with a stapler, of a conveyer for feeding pads with covers thereon to said stapler, means for delivering 80 covers having binding flaps to said conveyer, means for turning the binding flaps, a guide disposed parallel with said conveyer for supporting the upturned binding flaps, a pad hopper disposed at one side of the conveyer, a pad feeding member delivering the 85 pads to the conveyer upon the covers with the binding edges of the pads against the said upturned binding flaps, and means for folding the binding flaps upon the pads in advance of the stapler.

12. The combination with a stapler, of a conveyer for feeding pads with covers thereon to said stapler, means for delivering 90 covers having binding flaps and cover extensions to said conveyer with their ends projecting at each side thereof, means for turning the cover binding flaps to receive pads, means for delivering pads to said covers with their binding edges against the binding flaps, a cover extension turner member disposed at the rear of said pad delivery 100 means to turn the cover extensions up as the conveyer is actuated, said member being extended rearwardly and yieldingly supported to press against the front ends of the pads, a reciprocating folder for folding the cover extension down upon the pads, and a binding flap folder disposed to fold the binding flaps upon the pads.

13. The combination with a stapler, of a conveyer for feeding pads with covers thereon to said stapler, means for delivering 110 covers having binding flaps and cover extensions to said conveyer with their ends projecting at each side thereof, means for turning the cover binding flaps to receive pads, means for delivering pads to said covers with their binding edges against the binding flaps, a cover extension turner member disposed at the rear of said pad delivery 115 means to turn the cover extensions up as the conveyer is actuated, a reciprocating folder for folding the cover extension down upon the pads, a binding flap folder disposed to fold the binding flaps upon the pads, a traveling clamping means comprising sprocket chains mounted so that their lower reaches travel parallel with the conveyer and provided with members engaging with the pads during the stapling operation, and driving 120 125 130

means for the movable members synchronized with said conveyer.

14. The combination with a stapler, of a conveyer for feeding pads with covers thereon to said stapler, means for delivering covers having binding flaps and cover extensions to said conveyer with their ends projecting at each side thereof, means for turning the cover binding flaps to receive pads, means for delivering pads to said covers with their binding edges against the binding flaps, a cover extension turner member disposed at the rear of said pad delivery means to turn the cover extensions up as the conveyer is actuated, a reciprocating folder for folding the cover extension down upon the pads, and a binding flap holder disposed to fold the binding flaps upon the pads.
15. The combination with a stapler, of a conveyer for conveying to the stapler pads and covers having binding flaps and cover extensions, means for turning the cover binding flaps to receive a pad, a pad feeding means, a cover extension turner member adapted to turn the cover extensions up as the conveyer is actuated, a folder for folding the cover extension down upon the pad, a binding flap folder disposed to fold the binding flap upon the pad in advance of the stapler, and a traveling clamping means provided with members engaging with the pads during the stapling operation.

16. The combination with a stapler, of a conveyer for conveying to the stapler pads and covers having binding flaps and cover extensions, means for turning the cover binding flaps to receive a pad, a pad feeding means, a cover extension turner member adapted to turn the cover extensions up as the conveyer is actuated, a folder for folding the cover extension down upon the pad, and a binding flap folder disposed to fold the binding flap upon the pad in advance of the stapler.

17. The combination with a stapler, of a conveyer for conveying to the stapler pads and covers having binding flaps and cover extensions, means for turning the cover binding flaps to receive pads, a pad feeding means, a cover extension turner member adapted to turn the cover extensions up as the conveyer is actuated, a folder for folding the cover extension down upon the pads, and a binding flap folder disposed to fold the binding flaps upon the pads in advance of the stapler.

18. The combination with a stapler, of a conveyer for conveying pads and covers having binding flaps and cover extensions to the stapler, a binding flap turning means, means for supporting the upturned binding flaps, means for delivering pads to said covers against the upturned binding flaps thereof, means for folding the cover extensions upon the pads, means for folding the binding flap upon the pads, in advance of the stapler, and means engaging the folded cover extensions traveling with the conveyer.

19. The combination with a stapler, of a conveyer for conveying pads and covers having binding flaps and cover extensions to the stapler, a binding flap turning means, means for supporting the upturned binding flaps, means for delivering pads to said covers against the upturned binding flaps thereof, means for folding the cover extensions upon the pads and providing pressure against the outer ends thereof, and means for folding the binding flap upon the pads in advance of the stapler.

20. The combination with a stapler, of a conveyer for conveying pads and covers having binding flaps and cover extensions to the stapler, a binding flap turning means, means for supporting the upturned binding flaps, means for delivering pads to said covers against the upturned binding flaps thereof, means for folding the cover extensions upon the pads, and means for folding the binding flap upon the pads in advance of the stapler.

21. The combination with a stapler, of a conveyer for conveying pads and covers having binding flaps and cover extensions to the stapler, means for turning the binding flaps of the covers, a pad feeding means, means for folding the binding flaps upon the pads in advance of the stapler, and means for folding the cover flap extension.

22. The combination with a stapler, of a conveyer for conveying pads and covers having binding flaps to the stapler, means for turning the binding flaps of the covers, a pad feeding means, and means for folding the binding flaps upon the pads in advance of the stapler.

In witness whereof I have hereunto set my hand and seal in the presence of two witnesses.

DANIEL A. HOPPING. [L. S.]
